UNITED STATES PATENT OFFICE.

HANS NIELSEN, OF MINNEAPOLIS, MINNESOTA.

HARNESS-BUCKLE.

No. 922,500.

Specification of Letters Patent. Patented May 26, 1909.

Application filed September 5, 1908. Serial No. 451,894.

To all whom it may concern:

Be it known that I, HANS NIELSEN, a citizen of the United States, residing at Minneapolis, in the county of Hennepin and State of Minnesota, have invented a new and useful Harness-Buckle, of which the following is a specification.

My invention relates to improvements in harness; and has special reference to the form and appliance of a buckle with certain parts of the harness.

The object will appear from the description of the accompanying drawing, in which—

15 Figure 1 is a side elevation of a horse in dotted outline and some parts of a harness thereon with my invention applied thereto: Fig. 2 is a perspective detail view of the improved buckle only.

20 Referring to the drawing by reference numerals, 1 designates a horse upon which the hames 2, back band 3, belly band 4, and tugs 5 of a harness are shown.

From the lower part of the girth or belly band 4 extends forwardly between the horses legs the martingale 6, whose front end is passed over the end of the neck yoke 7, on which it is guided by a staple-shaped guide 8, and has secured in it at 9 the tongue-holding middle bar 10 of a buckle 11 of the novel form shown in Fig. 2; the chape end 12 after being taken over the neck-yoke is returned, passed into the large loop 13 of the buckle and held by the tongue 14 in such adjusted position as will give the martingale the desired length. The buckle has another and shorter loop 15 extending from the ends of the tongue bar 10 and disposed at an angle to the loop 13. The terminal bar 16 of the loop 40 15 is round so as to wear as little as possible on the supporting strap 17, which is passed through the loop 15, is engaged with the hame coupling or fastener 18 (not clearly shown as any known form will do), and has 45 its ends adjustably secured together by a buckle 19, having a tongue 20 engaging the chape 21, the buckle being secured in the end 22 of the strap.

From the above description it will be seen that my improved buckle and its combination with the harness enable the same one buckle to support the neck yoke and the martingale and adjust the length of the latter

and to hold the supporting strap 17 to a certain place on the martingale, while in harnesses heretofore constructed the strap 17 is usually provided with a ring sliding and wearing on the martingale, or if fixed to it requires that much more material and labor to produce no better but rather an inferior result to that produced by my cheaper and neater arrangement.

What I claim is:—

1. In a harness, the combination of the girth or belly band 4, a martingale strap having its rear end secured thereto and its front end formed with a loop adapted to engage over the neck-yoke, and having its lower run formed into a rearwardly extended chape, a buckle secured in the upper run of the loop 70 and having a downwardly and forwardly extending loop below the said run with a tongue therein for engaging the chape, and an upwardly extending loop above the upper run, and a cross bar between the two loops of 75 the buckle inserted in the upper run of the strap loop and supporting the pivoted end of the tongue, and a supporting strap adapted to connect the upper loop of the buckle with the hame of the harness. 80

2. In a harness, the combination of the girth or belly band 4, a martingale strap having its rear end secured thereto and its front end formed with a loop adapted to engage over the neck-yoke, and having a lower run 85 formed into a rearwardly extended chape, a buckle secured in the upper run of the loop and having a downwardly and forwardly extending loop below the said run with a tongue therein for engaging the chape, and an upwardly extending loop above the upper run, and a cross bar between the two loops of 90 the buckle inserted in the upper run of the strap loop and supporting the pivoted end of the tongue, and a supporting strap adapted 95 to connect the upper loop of the buckle with the hame of the harness said supporting strap being passed loosely through the upper loop of the buckle and having a buckle and chape whereby its length may be varied. 100

In testimony whereof I affix my signature, in presence of two witnesses.

HANS NIELSEN.
